Mich., assignors to George M. Holley and Earl
Holley

Application October 16, 1944, Serial No. 558,917

3 Claims. (Cl. 123—102)

1

The object of this invention is to protect a marine engine from excessive speed and the resulting excessive supercharger pressure. Specifically, when a boat is traveling fast in a rough sea, rough enough to raise the propeller out of the water, the engine which drives the boat has a tendency to race, and dangerous speeds and supercharger pressures naturally result.

To prevent this, it is customary to interrupt the electric circuit of the engine ignition by means of a centrifugal governor, but when the ignition circuit is restored, which happens immediately after the speed has been reduced, the engine fires into the exhaust passages. These are full of explosive mixture, and the resulting explosion in these exhaust passages is very trying to the nervous system and is almost as bad for the engine and its accessories. Noise is most objectionable for other reasons. The sudden resumption of power imposes a shock on the engine and transmission. If the power is interrupted, the power can be restored after a few seconds or even minutes, as the propeller will continue to rotate and the engine will not stall for a considerable period of time due to the speed of the boat through which the boat is traveling.

The object of this invention therefore is to interrupt the ignition and the fuel flow at excessive speeds for a sufficient period of time to prevent any explosions in the exhaust pipes. This object is alternatively achieved by positively locking the ignition switch in the open position and positively closing a flow control device to prevent the flow of fuel to the fuel flow of the nozzle and thus compelling the operator in order to restart the engine, to positively unlock the fuel flow control device and to replace the ignition switch in the operative position. This gives the operator an opportunity to close the throttle before restarting. Thus a period of high suction follows a period of excessive speed which protects the engine by increasing the lubrication of the pistons. The closure of the throttle, when the engine is rotating at any considerable speed, causes a suction in the cylinder which causes oil to be drawn up the cylinder walls, which thus lubricates the pistons.

Figure 1 shows diagrammatically the preferred form of our invention applied to the standard marine carburetor for the larger engines.

Figure 2 shows a simpler construction.

Description—Figure 1

In Figure 1, air enters an air inlet pipe at 10, fuel under pressure flowing through the passage 11 is regulated by the fuel needle 12 past the metering orifice 28. Fuel entering the carburetor at 68 is controlled in the diaphragm chamber 55 by diaphragms 24 and 25 which control needle

2

valves 24' and 25'. Air chambers 26 and 27 determine the pressure of the fuel in the chamber 68 and are connected together through a passage 21, chamber 26 receiving atmospheric air pressure through opening 26' from the metering orifice 28.

Fuel descends through the passage 29 and discharges through the fuel nozzles 30 and 31 into the inlet pipe adjacent the throttle valves 13 and 14. Throttles 13 and 14 vary the air flow around the fuel nozzles 30 and 31. Gears 16 and 17 are connected to the throttles 13 and 14 and engage with the small gear 15 actuated by lever 53, which thus determines the relative position of the throttles 13 and 14. A spring 20 pressing against an end of a lever 21 pushes a roller 22 mounted on lever 21 against the face of the cam 19 mounted to rotate with lever 53 and gear 15. The movement of the needle 12 engaging the opposite end of the lever 21 is thus controlled by the lever 53 through the lever 21 and the cam 19 mounted on the lever 53.

The air flows through the passage 32 to a supercharger contained in a casing 33. The supercharger pressure is communicated from casing 33 through a pipe 34 to a chamber 35 containing the barometric element 36. Electric contact 37 is carried by the barometric element 36, contact 38 is carried by the spring 41 supported at one end on the base 45. The eccentric 43 adjusts the position of the free end of spring 41, and hence the location of the movable contact 38. Conductor 39 is connected to a storage battery 70 and to the contact 38. The opposite terminal of the battery is grounded. A manually-operated switch 101 may be provided in the circuit, including the barometric contacts 37—38.

The contact 37 is connected to a conductor 42, which is connected to a terminal of a solenoid 44, which has its other terminal grounded, to thus complete a solenoid-controlled circuit. The solenoid is inside a magnetic element 47, which attracts an armature 48 and holds it in a retracted position so long as the solenoid circuit is closed 45 against the force excited by a compression spring 49. A vertically-slidable handle 50 is thus held in its lower position, and it can also be held in this position by a lock 23 or safety catch so that in the position shown, it would not be subject to the energizing of solenoid 44 or affected as far as the supercharger pressure is concerned. The rod 102 is engaged by the lock 23 and is carried by the armature 48; hence, the armature 48, when lock 23 is in the position shown, does not respond to excessive supercharger pressure. The element 23 can be rotated so as to leave the armature 48 free to be raised by the spring 49 when the contact 37 moves away from the contact 38 and the current which makes 47—48 an

electromagnet is interrupted due to excessive supercharger pressure.

A circuit breaker 72 is connected to a terminal of battery 73 through a pair of contacts 74, the opposite battery terminal being grounded. Circuit breaker 72 is also connected to one end of a low-tension coil 75, its opposite end likewise being grounded. A high-tension coil 76, having one end grounded and the other end connected to a rotating element 76, is energized by coil 75, which provides high tension electricity to the rotating high tension element 76, which provides electricity for the distributor 77.

A fuel shut-off valve 78, controlled by an electromagnet 79 grounded at 79' and connected to circuit breaker 72, attracts an armature 80 and thus opens the valve 78 whenever the current is flowing. Whenever the current for the distributor is flowing through contacts 74, there is current flowing through the electromagnet 79. When contacts 74 are opened, no current flows through 79 and valve 78 closes, the element 80 is attracted (magnetically) by the solenoid 79 at such times as the solenoid 79 is energized by current flowing through it. When the solenoid 79 is energized, the valve 78 is raised into the position in which it is shown so that fuel can then flow from the diaphragm chamber 68 to the fuel passage 11-29 and restriction 28 and past the control valve 12. The upper half of the pair of contacts 74 are mounted on the handle 50.

Operation—Figure 1

In the normal operation of the device, throttles 13 and 14 are open and the contacts 74 are closed by depressing handle 50. Thus, the circuit breaker 72 controls the ignition through the distributor 77. When the safety catch 23 is not in the way, contacts 74 are opened whenever the supercharger pressure in chamber 33 rises high enough to open the contacts 37 and 38. This occurs when the speed of the engine is excessive. When this happens, the spring 49 pushes the armature 48 away from the stationary element 47 and contacts 74 are opened, and in order to restart the engine, the plunger 50 must be pushed back into place to complete the circuit through contacts 74.

Meanwhile, the valve 78 has dropped down to prevent the flow of fuel during deceleration and until after the engine has been restarted when the valve 78 is reopened simultaneously with the restoration of electric current to the distributor circuits 72-75-76-77.

During the time that no spark was generated, no fuel flowed as valve 78 was seated. Hence, there is no longer a tendency for the engine to fire in the exhaust passages so that the engine resumes its normal functioning quietly without explosion in the exhaust passage. If only the fuel flow is interrupted, a back fire may result from fuel still remaining in the intake passages.

Description—Figure 2

84 is a shaft driven by the engine, 85 is a centrifugal governor which engages through a lever 89 with a differential switch 86, which is placed in an electric circuit between a battery 87 and a manually-operated ignition switch 88. The circuit breaker 72, coil 75 and high tension distributor 76-77 are as shown in Figure 1. The solenoid 79, armature 80 and valve 78 are also as shown in Figure 1. The switch 88 is arranged to cause the valve 78 to drop so as to cut off

the flow of fuel and to simultaneously open the ignition circuit 87-86-88, 72, 75 and ground.

Operation—Figure 2

When the switch 88 is open, the cut-off valve 78 is closed; when switch 88 is closed, then the governor 85 controls. When speed exceeds, say 2800 revolutions per minute, the differential switch 86 opens the circuit 87-86-88-79 and the ground. The opening of this circuit permits the valve 78 to close and at the same time the circuit 87-86-88-72-75-ground is opened so as to interrupt the functioning of the ignition distributor 76-77. When the speed falls to say 2500 revolutions per minute, the differential switch 86 operates so as to re-establish these circuits so that the ignition circuit is re-established and at the same time the valve 78 is opened. The lever 89 is designed to both open and close the electric circuit, that is, to open the circuit at 2800 revolutions per minute and to close the circuit at 2500 revolutions per minute.

If the centrifugal governor 85 is connected to the differential switch 86, which switch is connected only to the circuit of the solenoid 79 and not to the ignition circuit, then the device would function without interrupting the ignition circuit. If the speed exceeded a predetermined speed of the governor, the valve 78 would close, but the ignition would continue. A slight backfire would probably result, but it would not be as noticeable as the backfire now experienced. Hence, the device would be an improvement on the existing devices if the governor 85 merely controlled the solenoid 79, armature 80 and valve 78 and did not interrupt the ignition.

It will be noticed that opening the manually-operated switch 88 of Figure 2, or opening the manually-operated switch 74 of Figure 1, normally opens the ignition circuit and automatically stops the discharge of fuel. This is of great importance when using "hot" plugs, as these plugs frequently cause the engine to fire automatically if the engine circuit has been opened without closing the fuel outlet. The electro-magnetic responsive valve 78 by shutting off the fuel supply prevents such "hot" plugs causing the engine to fire when the operator attempts to stop the engine by cutting the ignition.

In order that the marine engines shall idle indefinitely, the plugs are so designed that they will remain cleaned and free of carbon, and therefore they are usually of the "hot" type.

By opening switch 88 (Figure 2) or the switch 74 (Figure 1), the fuel is cut off by valve 78 at the same moment that the ignition circuit is opened and the engine quits firing instantly regardless of how hot the plugs may be.

What we claim is:

1. A safety device for a supercharged internal combustion engine of the electric ignition type having an engine driven supercharger, the pressure of which increases with engine speed, a carburetor with a liquid fuel supply passage incorporated in the carburetor and delivering liquid fuel to the engine, automatic means responsive to an increase in the supercharger pressure for simultaneously interrupting the flow of liquid fuel to the engine and also the flow of electricity to the ignition system, manually operated means for re-establishing the liquid fuel flow and the ignition circuit.

2. A safety device for a supercharged internal combustion engine having an engine driven

supercharger, the pressure of which increases with engine speed and a carburetor having a fuel supply passage incorporated in the carburetor and delivering liquid fuel to the engine, a valve in said liquid fuel passage, electro magnetic means for opening said valve, an electric circuit therefor, a pair of contacts in said circuit means responsive to an excessive supercharger pressure for separating said contacts.

3. A safety device for supercharged internal combustion engine of the electric ignition type having a liquid fuel supply passage and a cut-off valve therefor, an electrically operated sole-

noid adapted to hold said valve open, yieldable means for opening the electric circuit of said solenoid, a second electrically operated solenoid adapted to hold the circuit closed of said first solenoid and to hold said yieldable means compressed, means responsive to an excessive supercharger pressure for opening the electric circuit of the second solenoid, manual means for opening and closing said circuit of said second sole-

10 noid.
